UNITED STATES PATENT OFFICE.

MARCEL ACHART, OF PARIS, FRANCE.

SUPPORTING DEVICE FOR THE HEELS OF FOOTWEAR.

Application filed May 25, 1921. Serial No. 472,325.

To all whom it may concern:

Be it known that I, MARCEL ACHART, a citizen of the Republic of France, residing at 21 Rue Victor Masse, city of Paris, France, have invented certain new and useful Improvements in Supporting Devices for the Heels of Footwear; and I do hereby declare that the following is a full, clear, and exact description of the invention, such as will enable others skilled in the art to which it appertains to make and use the same.

The heels used for boots and specially ladies' shoes are rarely fastened securely to the sole for resisting for a long time the oblique force caused by walking. Thus, after a short usage, the nails or pins which fasten the heel to the sole, instead of remaining perpendicular to the sole, become inclined bit by bit and the heel gradually gives way under the weight of the body, often causing the fall of the person booted with these shoes. Moreover, the heels wear unequally.

The supporting device which is the object of the present invention remedies these defects. This supporting device consists of a metal plate or stiffening square made of two branches from a single piece forming between them an angle corresponding to the one made by the meeting of the internal straight or curvilinear face of the heel with the interior straight or curvilinear face of the shank of the sole. Each of these branches is provided with holes for the placing in of the screws fitting, one hole in the heel, and the other hole in the shank of the sole and the points, hooks, clasps are emplanted in these parts of the shoe, or better each of these branches is provided with one or the other of these means of attachment.

This stiffening square should be light and also very strong, more so in its application to shoes to harmonize with the parts by which it rests in the proper manner to preserve the outline of the shoe and to be elegant.

It is in this character that the various conformations of the stiffening square represented in the accompanying drawing have been designed.

In the accompanying drawing:—

Fig. 1 is a plan view of a shoe sole showing the support in position.

Figs. 2 and 3 show in side elevation two

forms of shoes with the support in position.

Fig. 4 shows a shoe illustrating the collapse of the heel after a short usage when not fitted with a device according to the invention.

Fig. 5 shows a supporting device for a shoe in longitudinal elevation and seen from the face attached against the arch of the sole.

Figure 6 is a plan view of the same.

Fig. 7 shows a modified construction of this supporting device in longitudinal elevation.

Figure 8 is a plan view of the same.

Fig. 9 shows in perspective the supporting device applicable to a different type of footwear in which the metal plate is of channel section.

Fig. 10 shows in plan, seen from the face attached to the shank of the sole, the variation of the supporting device, shown in Fig. 9.

Fig. 11 shows the various dispositions at the end of the supporting device of the type shewn in Fig. 9 which sinks down and so is fixed on the shank of the sole.

Fig. 12 shows in perspective the supporting device in which the metal plate is channel-shaped in transverse section.

Fig. 13 is a transverse section of the plate forming the channel.

A shows the heel, B the shank of the sole, C the supporting device applied on the heel and this shank.

As is shewn in Fig. 1, the line *a b* is longer than the line *c d*; consequently the side *a b* of the sole is less resisting than *c d* and this lesser resistance, in showing itself by an oblique movement, causes an irregular wear of the treading face of the heel A. In applying the device C on the shank B face to face from the centre of the width of the heel A, one gives a much greater rigidity to the sole of the boot in these parts and the heels do not "turn" any more; one also avoids the sinking of the heel such as is shewn in Fig. 4.

The supporting device in the various positions shewn in Fig. 5 to 12 as made of a metal plate, made if necessary in tempered steel, is composed of two branches of a single piece 1 and 2 forming between them an angle. The branch 1 applies itself against the shank B of the sole; the branch 2 against the heel A. The angle of these two branches is curvilinear in the case where

the supporting device applies to the Louis model shoe so that this part carries the curve of the heel.

In the construction shewn in Figs. 5 and 6, the plate 1 is pierced at plate 11 in one part of its length; it is provided at its extremity at both sides with hooks 12 and at the rear of such hooks with points 13. The hooks and points are introduced into holes 10 pierced previously in the shank B of the sole, these points 13 preventing the hooks 12 from being disengaged when positioned.

The nail or screw lodged in the hole 5 keeps this branch on the shank. The branch 15 2 is curved at its end to form a centre point 14; this centre point 14 is driven into the heel, security being obtained by means of a nail or screw inserted through the hole 15.

In the construction shewn in Figs. 7 and 20 8, the supporting device is made of two laterally curving wire plates 1 spaced from each other by a pierced part 16; the wires have the curve of the external face of the heel A and of the internal of the shank B; 25 they are joined from the side of the shank B by a transverse member 17 at the centre of the length of which is a spear 18 previously implanted into the shank; the ends of the wires 1 opposite the transverse member 17 are bent to form points 14 which are imbedded in the heel A. A transverse bar 19 placed a short distance from the pointed ends 14 is pierced by a hole 5 for the reception of a nail or screw.

35 In the construction of the supporting device represented in Figs. 9, 10 and 12 the metal plate instead of being straight in the transverse sense is curvilinear as represented in Fig. 13 and makes the form of a channel 40 20 having rims 21 which, when applied to the shank B and against the heel A, oppose the entry of the dust and mud in the channel, the curve 20 forming a rim in the plate composing the device.

45 In Figs. 9 and 10, the branch 1, which is applied against the shank, is turned at its end against the upper part after having been cut to form the two points 22 bevelled at 23 outside to their extremity (see Fig. 11). In 50 forcing these points into the sole, they incline and approach one another thus following the dotted lines shown in the profile, Fig. 11; between these points 22, the edges are cut into one or two points 24 which are pressed into the leather. The bevels 23 are 55 then placed inside in this case, causing the

points 22 to turn aside outwardly in the leather.

As may be seen from the profile, Fig. 11, a notch 25 may be cut in the internal face 60 of these points 22, about the middle of their length, at the point where the bevels penetrate the leather, the points 22 in bending being thus caused to take up the position shown in dotted lines. 65

The hooks 23 and 26 enter the leather and firmly retain the device against the sole and the teeth 24 entering at the end of the sinking down portion tighten the leather opened by the parting of the hooks 23 or 26. 70

The longitudinal edges 21 (Figs. 9 and 10) are provided nearly at the end 2 with hooks 27 which penetrate into the holes previously pierced in the sole. The edges 21 may also be serrated as at 28. The device is pierced 75 with holes 5 for holding screws.

The curved part 2 which may be applied against the heel A may be provided in respect of the edges of the channel with 80 points 30 intended to penetrate the heel at the proximity of the sole. The edges 21 of the curved part 2 are provided at their internal extremity with saw teeth 31 which are imbedded in the heel; the bottom of the channel is split at 32 to accommodate a 85 screw.

In the construction of the device shewn in Fig. 12, the extremity of the branch 1 is constructed in the same fashion as the corresponding extremity of the branch 1 90 of the device shewn in Figs. 9 and 10. The curved part 2 is cut on the edges 21 with saw teeth 31 and the bottom of the channel 20 is pierced with a hole 33 or split at 32 to receive a screw. 95

What I claim and desire to secure by Letters Patent is:—

A supporting device for heels of footwear comprising a metal plate consisting of a shank section and a heel section extending 100 a curvilinear angle, hooks extending from the opposite sides of the free end of said shank section, points formed with the free end of said shank section and extending 105 at an angle with respect to said hooks, serrations formed with the opposite end of said shank section, and hooks formed with said heel section substantially as and for the purpose specified.

In witness whereof I have hereunto set 110 my hand.

MARCEL ACHART.
